(57) CLAIM

The ornamental design for a door hinge mask, as shown and described.

DESCRIPTION

FIG. 1 is a perspective view of a door hinge mask showing my new design;

FIG. 2 is a front elevational view thereof;

FIG. 3 is a right side elevational view thereof;

FIG. 4 is a top plan view thereof; and,

FIG. 5 is a perspective view of a door hinge mask shown on a roll of painter's tape;

The broken line showing of environmental structure is for illustrative purposes only and forms no part of the claimed design.
